DESIGN FOR A SHAVING BOWL OR SIMILAR ARTICLE

Frank McIntosh, New York, N. Y., assignor to Lenthalic Incorporated, New York, N. Y., a corporation of New York

Application May 16, 1941, Serial No. 100,981

Term of patent 7 years

To all whom it may concern:

Be it known that I, Frank McIntosh, a citizen of the United States, residing at New York city, in the county of New York and State of New York, have invented a new, original, and ornamental Design for a Shaving Bowl or Similar Article, of which the following is a specification, reference being had to the accompanying drawing, forming part thereof.

In the drawing:

Fig. 1 is a top plan view of a shaving bowl embodying my new design;

Fig. 2 is a front elevational view; and

Fig. 3 is a rear elevational view thereof.

The sides of the handle are plain surfaces.

I claim:

The ornamental design for a shaving bowl or similar article, substantially as shown and described.

FRANK MCINTOSH.
